US00D700763S

(12) **United States Design Patent**
Sharp

(10) **Patent No.:** **US D700,763 S**
(45) **Date of Patent:** **** Mar. 4, 2014**

(54) **PALLET AND PRODUCT PROTECTOR**

(71) Applicant: **Geoffrey Richard Sharp**, Visalia, CA
(US)

(72) Inventor: **Geoffrey Richard Sharp**, Visalia, CA
(US)

(**) Term: **14 Years**

(21) Appl. No.: **29/440,178**

(22) Filed: **Dec. 19, 2012**

(51) LOC (10) Cl. **12-05**

(52) U.S. Cl.

USPC **D34/35**

(57) **CLAIM**

The ornamental design for a pallet and product protector, as shown and described.

DESCRIPTION

FIG. 1 is a front isometric view of a pallet and product protector, showing my design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken line showing in the drawings is included for the purpose of illustrating portions of the pallet and product protector and forms no part of the claimed design.

1 Claim, 5 Drawing Sheets
